UNITED STATES PATENT OFFICE.

ALBERT J. McNALLEN, OF GORE, OHIO.

TUBING AND PACKING FOR OIL-WELLS.

1,173,825.

Specification of Letters Patent. Patented Feb. 29, 1916.

Application filed March 30, 1915. Serial No. 18,038.

To all whom it may concern:

Be it known that I, ALBERT J. McNALLEN, a citizen of the United States of America, residing at Gore, in the county of Hocking and State of Ohio, have invented certain new and useful Improvements in Tubing and Packing for Oil-WellS, of which the following is a specification.

The present invention relates to tubing and packing for oil wells, and is designed especially for the purpose of improving the construction of the packing and joints in the well tubing and barrel of the oil pump in order to prevent waste or loss of oil, and make the glands and packing material tight-fitting in their tubes.

The invention consists essentially in certain novel combinations and arrangements of parts for accomplishing the above purpose as will be hereinafter more fully described and claimed, reference being had to the accompanying drawings in which I have depicted one form of the physical embodiment of my invention which has proven highly satisfactory and efficient.

Figure 1 is a partial sectional and partial elevation view, showing the upper end of the oil pump tube and oil outlet therefrom and the pump barrel and cable, showing also the socket at the lower end of cable. Fig. 2 is a sectional view on line A—A of Fig. 1. Fig. 3 is a view similar to Fig. 2 but showing the jaws of the clamp device opened, to give access to the sectional parts of the gland. Fig. 4 is a plan view of the upper end of the oil well tube showing the sectional gland therein. Fig. 5 is an enlarged detail sectional view, showing the manner of securing the cable to the socket.

In illustrating the construction and application of my invention I have utilized the usual oil tube 1 forming part of the pumping device and including the T section or coupling 2 with the oil outlet 3 to which the bushing 3' is connected by the threaded coupling sleeve 4.

The bushing as clearly shown is open at the top and formed with a pair of perforated and threaded ears or lugs 5, 5, projecting from its upper edge, while near its lower end, which is of reduced diameter, an annular shoulder 6 is fashioned upon which shoulder the lower sections 7, 7 of the packing gland are seated. The upper sections 8, 8, of the gland are separated from the lower sections 7 by the packing

material 9 of suitable type or character, and each of the four gland sections is formed with hemispherical grooves for the free movement of the pump barrel 10 which reciprocates through the packed gland.

To hold the glands and packing securely in the bushing, I employ a clamping member comprising the two hinged jaws 11 and 12 which freely swing on the threaded bar 65 or bolt 13 as their pivot. This bolt is adapted to thread into one of the ears 5 of the bushing and has on its upper end a lock nut 14 and clamp nut 15, the latter bearing upon the top edge of the jaws at 70 their hinged joint. In Figs. 2 and 3 it will be seen that these jaws are provided with curved portions 11' and 12' which fit around the barrel 10, but do not interfere with the movement of the barrel. At their ends the 75 jaws are clasped by means of the yoke 16 which is fixed to the jaw 12 by the bolt 17 and detachably connected to the jaw 11 by the bolt 18. In Fig. 1 it will be seen that the longer jaw 12 is provided with a 80 slot 19 near its end in which the bolt 17 is slidable, and by this means the yoke may be moved to clasp over the end of the shorter jaw 11, or moved outwardly to free the jaws from each other. When the jaws are 85 brought together they fit about a threaded bolt 20 which is threaded into the other ear 5, and this bolt is also provided with a clamp nut 21 and lock nut 22. Thus, when the parts are assembled as in Fig. 1, the 90 gland sections may be securely pressed down in the bushing by turning the clamp nuts on the bolts 13 and 20, and then these nuts may be locked against turning by the lock nuts 14 and 22. The jaws thus bear 95 upon and hold the glands in the bushing forming an air and oil tight closed top or housing for the oil tube and preventing the escape of oil therethrough.

Above the packed joint or housing a similar 100 but smaller bushing 3^a is screwed to the barrel 10 and the gland sections 7' and 8' and clamping member 13' provide a tight joint for the cable 14' and provide a liquid tight joint. The cable of course may 105 pass down through the packed gland until the pumping sinker has reached its desired depth, and then the cable may be clamped and held between the clamp member 13' and as will be understood.

In Figs. 1 and 5 the improved manner of fastening the socket 23 to the spread end

of separate strands 24 of the cable 14' permits the use of a small but strong socket, of a size to pass freely through the barrel 10, thus avoiding the usual necessity of cutting the socket from the cable before it can be passed through the barrel. The socket is threaded externally to receive the sinker (not shown), and perforations are formed in the socket to receive the unraveled end of the cable which is then leaded or "babbitted" to make a secure fastening.

The jaws of the hinged clamps may be opened to give access to the glands of the packing and the sectional construction of these glands facilitates the replacing and renewing of worn parts without recourse

to the usual laborious proceeding, thus saving considerable time and expenditure of energy, in attending to these duties.

What I claim is:—

The combination with an interiorly shoulered oil well tube provided with exterior perforated ears, a sectional packing gland in the tube, and threaded bolts in the ears, of a pair of clamping jaws having a hinge joint on one of the bolts, means for fastening the free ends of said jaws together about the second bolt, and clamping nuts on said bolts for forcing the jaws upon the gland.

In testimony whereof I affix my signature.

ALBERT J. McNALLEN.
